UNITED STATES PATENT OFFICE.

PETER FLANSBURG, OF MANISTEE, MICHIGAN, ASSIGNOR, BY MESNE ASSIGNMENTS,
TO A. J. MCKAY, OF CHICAGO, ILLINOIS.

BERRY BOX.

Application filed December 8, 1921. Serial No. 520,905.

To all whom it may concern:

Be it known that PETER FLANSBURG, a citizen of the United States of America, residing at Manistee, in the county of Manistee and State of Michigan, has invented new and useful Improvements in Berry Boxes, of which the following is a specification.

The object of the invention is to provide a simple and efficient berry box which can be constructed of a cheap material, free from the objections which are incidental to the use of splint or veneer wood which are subject to warping and splitting and furthermore to provide a box which can be struck from a single blank of pliable material adapted to be produced by stamping from a sheet of the material and shipped to the consumer in a flat condition, and which can be set up by the consumer and locked in the proper shape for containing the product with the minimum expenditure of time and effort; and with these objects in view the invention consists in a construction and combination of parts of which a preferred embodiment is shown in the accompanying drawings, wherein:

Figure 1 is a perspective view of a box embodying the invention.

Figure 2 is a plan view of the blank from which the article is formed.

The receptacle which is of rectangular form although not necessarily square as indicated in the drawing, and which may be made of any desired capacity within the range of those ordinarily employed in the crating and shipment of berries, fruits and certain kinds of vegetables consists of a bottom fold 10 provided at its four sides with parallel sided extensions forming wall flaps 11 and 12 of widths corresponding respectively with the edges of the bottom fold from which they extend, the extremities of the diametrically opposite flaps 11 being provided with slits or kerfs 13 disposed substantially perpendicular to the end edges of the flaps, and the diametrically opposite flaps 12 being provided at their extremities with laterally extending tongues 14, two of which are provided with slits or kerfs 15 disposed substantially perpendicular to the outer edges of the tongues and adapted to be arranged in registering relation respectively with the slits or kerfs 13 of the flaps 11, and the other two of which are provided with

slits or kerfs 16 extending from the inner edges of the tongues and in oblique relation thereto or at an angle other than perpendicular and inclining inward toward the side edges of the flaps 12 for engagement with the slits or kerfs 13 and 15 in such a way as to straddle the inner ends of said slits or kerfs as indicated in Figure 1 and form an interlock therewith.

The bottom fold may be suitably perforated as indicated at 17 for ventilation, the diameters of the openings being such as to afford a circulation of air without permitting the contents of the box to escape, and in setting up the box it is only necessary to fold the several flaps thereof on the fold lines 11^a and 12^a into positions perpendicular with the plane of the base or bottom fold, and then turn the tongues 14 inward on their fold lines 14^a, first folding the tongues having the slits 15 into registration with the slits 13 and then folding the tongues having the slits 16 to overlap the first-named tongues and bringing the slits 16 into straddling relation with the registering slits 13 and 15. No fastening means other than the interlock thus provided is required in order to hold the box in the required form with the walls in perpendicular relation with the base or bottom, and should it be desired or expedient to use the box a second time the tongues may be readily disengaged to return the blank to a flat condition for economical storage pending such further use.

Having described the invention, what is claimed as new and useful is:

1. A box of foldable material formed from a single blank and having a rectangular bottom fold and flaps extending respectively from the several edges of said fold, diametrically opposite flaps being provided at their outer edges with an inwardly directed slit and the other diametrically opposite flaps being provided with lateral tongues, the ends of these tongues extending above the top of the first mentioned opposite flaps, the tongues carried by each of said flaps being provided with slits intersecting and extending respectively from the outer and inner edges thereof.

2. A box of foldable material formed from a single blank and having a rectangular bottom fold and flaps extending respectively from the several edges of said fold,

diametrically opposite flaps being provided at their outer edges with an inwardly directed slit and the other diametrically opposite flaps being provided with lateral tongues, 5 leaving spaces between the edges of the tongues and the first mentioned flaps, the tongues carried by each of said flaps being provided with slits intersecting and extending respectively from the outer and inner edges thereof, the slits in the outer edges of the first-named flaps and extending from the outer edges of said tongues being arranged substantially perpendicular to the edges with which they intersect, and the 10 slits extending from the inner edges of the other tongues being disposed in oblique relation with the edges which they intersect.

3. A box of foldable material formed from a single blank and having a rectangu-

lar bottom fold and flaps extending respectively from the several edges of said fold, diametrically opposite flaps being provided at their outer edges with an inwardly directed slit and the other diametrically opposite flaps being provided with lateral tongues, 25 the ends of these tongues extending above the top of the first mentioned opposite flaps, the tongues carried by each of said flaps being provided with slits intersecting and extending respectively from the outer and inner edges thereof, the tongues opposite the flaps forming a double wall substantially throughout their length when the box is assembled.

In testimony whereof he affixes his signature.

PETER FLANSBURG.
